UNITED STATES PATENT OFFICE.

CLARENCE JUSTIN MYERS, OF MIDDLETOWN, PENNSYLVANIA.

DESIGN FOR A GAME-BOARD.

SPECIFICATION forming part of Design No. 26,166, dated October 6, 1896.

Application filed June 22, 1896. Serial No. 596,543. Term of patent 3 years.

To all whom it may concern:

Be it known that I, CLARENCE JUSTIN MYERS, a citizen of the United States, residing at Middletown, in the county of Dauphin and State of Pennsylvania, have invented and produced a new and original Design for Games; and I do declare the following to be a full, clear, and exact description of the same, reference being had to the accompanying drawing, forming a part thereof.

This invention relates to a game designed to be played either by two, three, or four persons for amusement, each person being provided with two dice, one dice-cup, and suitable portable figures or characters designated as "kings," "knights," or "men," each player using one king and three knights or men, four sets being provided, each set of a different color, corresponding to the color of the various castles to enable the players to readily distinguish their paths.

The object of this invention is to provide an amusing and inexpensive game for parlor amusement adapted for independent players or for couples.

The figure is a plan view of the game-board.

The face is a plane surface appropriately illuminated, being preferably printed artistically in suitable colors upon paper or other material and pasted or otherwise secured to a suitable base or board, the latter being made of wood or suitable strawboard.

The leading features of my design consist in the plan of the various paths to be traversed by the representative characters of each player and in the artistic design and illumination of the board.

Referring to the drawing, the letters A, B, C, and D designate the paths for each player

and also any four suitable colors, as, for instance, A might be red, B blue, C brown, and D yellow.

E designates the goal at the center of the board, which each player strives to reach.

The board is square and of suitable size, the four corners of which are embellished each with a representation of a castle and illustrations of castles, knights in armor, and other suitable scrollwork. From the center of each corner a path leads toward the center of the board, first turning to the right, then to the left across the next corner, then to the left across the following corner, then to the left toward the center, and again to the left to the goal at the center, each path being subdivided by means of transverse lines into small blocks representing measured stages in the journey to the goal. The particular plan is better understood by reference to the drawing.

It will be understood that the surface of the board is plane, all the various characters and figures being printed or stamped lines. In addition to the various colors of the castles and paths suitable colors are used for ground-work in distinction to the others.

At various points on each path are representations of gates, bridges, and prisons suitably illuminated, so as to be distinguishable.

What I claim is—

The design for a game-board herein shown and described.

In testimony whereof I affix my signature in presence of two witnesses.

C. JUSTIN MYERS.
